UNITED STATES PATENT OFFICE.

SAMUEL B. WILLIAMS, OF BROOKLYN, NEW YORK, AND EARL S. GIBSON, OF RIDGEWOOD, NEW JERSEY, ASSIGNEES TO WESTERN ELECTRIC COMPANY, INCORPORATED, OF NEW YORK, N. Y., A CORPORATION OF NEW YORK.

TELEPHONE-EXCHANGE SYSTEM.

Application filed October 31, 1923. Serial No. 671,865.

To all whom it may concern:

Be it known that we, SAMUEL B. WILLIAMS and EARL S. GIBSON, citizens of the United States of America, residing at 5 Brooklyn, in the county of Kings and State of New York, and Ridgewood, in the county of Bergen and State of New Jersey, respectively, have invented certain new and useful Improvements in Telephone-Exchange Systems, of which the following is a full, clear, concise, and exact description.

This invention relates to telephone systems and particularly to systems in which automatic switching apparatus is employed.

15 The object of this invention is to increase the efficiency of telephone systems by shifting the preference of senders for switch controlling markers, with which they are connectible, under manual control.

20 A feature of the invention relates to an arrangement in which groups of register senders, each having access normally to a different controlling marker, and wherein manual means serves to render any group 25 connectible with another of said markers.

Another feature relates to the provision of a spare marker common to all groups of senders together with manual keys for rendering such marker first choice to any desired group of senders.

Referring to the drawing, Figs. 1 and 2, taken together illustrate a portion of an automatic telephone system sufficient to enable an understanding of the invention.

35 Fig. 1 shows in a diagrammatic manner, a group of register senders of the central office type, and a group of switch controlling mechanisms or markers together with a connecting medium for connecting said senders to the markers.

40 Fig. 2 illustrates, in diagrammatic fashion, a second group of senders together with a second connecting medium for connecting such senders to the markers illustrated in Fig. 1.

45 In systems of the character to which the present invention is particularly applicable, register senders are provided at the central office for receiving records of the called subscribers' lines. In addition to these senders, a number of switch controlling mechanisms or markers are also provided. These markers are arranged to be associated with the register senders at the time a call is taking

place for the purpose of receiving from the senders information relating to the wanted subscriber's line. Upon receiving this information, the marker is in a position to exercise control over the selective switches which establish a talking connection between the calling and called parties.

55 Because of the fact that it is economical to provide a large number of senders in comparison to the number of markers, it becomes expedient to divide the senders into a number of groups making each group of senders normally connectible to a particular one of the markers as its first choice.

60 With reference to the drawing, Fig. 1 illustrates a group of senders, two of which, 100 and 101 are shown. These senders appear in the multi-contact relay connecting device 105. Fig. 2 illustrates a second group of senders of which the senders 200 and 201 are a part. This group of senders 65 appears in the multi-contact relay connecting device 205. A number of markers, 102, 103 and 104 are shown, each having an appearance in each of the connecting devices 105 and 205. It will be understood that additional groups of senders may be involved, each group appearing in similar connecting devices. The markers shown and such others as may be provided are multiplied 70 so as to have an appearance in all of the 75 connecting devices.

80 The group of senders including senders 100 and 101 is arranged to have access normally to the marker 102, the circuits being so taken that only one sender at a time may 85 be connected to this marker. Likewise, the group of senders including senders 200 and 201 normally have access to the second marker 103 as their first choice.

90 The third marker shown, namely, marker 104, is a 95 spare equipment and may be rendered available to the senders of any of the several groups as will be pointed out hereinafter. If, for any reason, the marker which normally serves a given group of senders should 100 be taken out of service temporarily, or, if for any other cause it is desired to shift the preference this may be done by manipulating certain keys shown in Figs. 1 and 2. The manipulation of these keys serves, for 105 example, to render marker 103 available as first choice to the group of senders 100, 101. In a like manner, the manipulation of these

keys may serve to render the marker 102 as the first choice marker of the group of senders 200, 201.

The general character of central office register senders, such as are suitable for employment in a system of this character, is well known in the art. The switch controlling devices or markers disclosed diagrammatically in this case are also in their general nature similar to register senders in that they receive records of calling lines and control in accordance therewith the setting of automatic switches. For a more detailed description of equipment of this character, reference is made to the application of S. B. Williams, Serial No. 596,179, filed October 23, 1922.

With particular reference to the detailed operation of the circuits, assume that it is desired to associate the sender 100 with its first choice marker 102. When it is desired to effect a connection between the sender 100 and the marker 102 the relay 112 is operated by means of a circuit completed over conductor 121 in any suitable manner. Relay 112 causes the operation of relay 114 in a circuit from battery through the lower winding of relay 114, lower front contact of relay 112, lower back contact of relay 111, left back contact of relay 116, and left back contact of slow relay 115 to ground. Relay 114 operates and causes the operation of relay 115 over a circuit from battery, through the winding of relay 115, inner right back contact of relay 116, lower contact of relay 114, and upper contact of relay 112 to ground. Relay 115 operates relay 116 and provides a holding circuit for relay 114 as follows: battery, through the upper winding of relay 114, inner upper contact of said relay, inner upper contact of relay 113, winding of relay 116, continuity contact and left armature of relay 115 to ground. Relays 114 and 116 lock in a circuit from battery, through the upper winding and inner upper front contact of relay 114, inner upper back contact of relay 113, winding and inner right contact of relay 116, lower contact of relay 114 and upper contact of relay 112 to ground. Relay 116, in operating, releases the relay 115. After an interval, relay 115 becomes fully released and operates the multi-contact relay 110 which is individual to the marker 102 in the connecting device 105. The circuit may be traced from ground, through the right contact of relay 115, outer right contact of relay 116, back contact of relay 117, key 118 and its normal contact, winding of the multi-contact relay 110 to battery. Furthermore, the relay 115, in releasing, operates the multi-contact relay 106 whereby the conductors leading from the sender 100 are connected to the corresponding conductors of the connecting device 105. The circuit for

this purpose may be traced from ground, through the left contact of relay 115, left front contact of relay 116, uppermost contact of relay 114, winding of relay 106 to battery. Thus, with relays 106 and 110 both operated, the sender 100 is connected through the conductors of the connecting device 105 to the marker 102.

Since the relay 116 remains operated in series with the relay 114, other senders are prevented from interfering with the existing connection. For instance, if the sender 101 should attempt connection, relay 111, individual thereto, in operating would not succeed in closing the circuit for the relay 113 due to the fact that relay 116 is energized.

When the connection is no longer desired between the sender 100 and the marker 102, the relay 112 is released by opening the circuit of the conductor 121. Relay 112 causes the release of relays 114 and 116. Relay 114 causes the release of relay 106 and relay 116 releases relay 110. Thus, the sender 100 is disconnected from the marker 102.

In a manner similar to that described above in detail, one of the senders 200 or 201 of the second group of senders may obtain connection with the first choice marker 103. If, for instance, the sender 201 is functioning to connect with a marker, relay 211 in operating causes the operation of relays 213, 215 and 216. Relay 215 then releases and causes the operation of the multi-contact relays 207 and 209. With the multi-contact relays operated, the sender 201 is connected through the device 205 to the marker 103. If the sender 200 desires connection with the marker 103, relay 212 is operated. Relay 212 causes the operation of relays 214, 216 and 215 whereupon the multi-contact relays 206 and 209 are operated and the sender 200 is connected through the device 205 to the marker 103.

It will next be assumed that for some reason or other it is desirable to remove the marker 102 from service. In order not to deny service to the group of senders 100, 101, the marker 103 which normally serves as first choice for the group of senders 200, 201 may be placed for the time being at the disposal of senders 100, 101 as well. To accomplish this, the keys 118 and 119 are thrown to their operated positions. When now the sender 100 desires to be connected to a marker and relay 112 is operated, it in turn causes the operation of relays 114, 115 and 116. Relay 115, after an interval, releases and closes a circuit for relay 221 traceable from ground, over the right contact of relay 115, outer right contact of relay 116, back contact of relay 117, front contacts of keys 118 and 119, conductor 122, winding of relay 221 to battery. Relay 221 causes the operation of relay 222 in a circuit from

battery, through the lower winding of the device 205. This is due to the fact that the latter relay, lower front contact of relay 221, common control relay 216 is held energized in series with the relay 222.

assuming that neither of the senders 200 and

5 201 is attempting connection at this time,

left back contact of relay 216, and normal

left contact of relay 215 to ground. Relay

222 causes the operation of relay 215 in a

circuit from battery, through the winding of

10 the latter relay, inner right back contact of

relay 216, lower front contact of relay 222

and upper contact of relay 221 to ground.

The operation of relay 215 causes the opera-

tion of relay 216 in the following circuit:

15 battery, through the upper winding and up-

per inner contact of relay 222, upper back

contacts of relays 214 and 218, winding of

relay 216, and continuity contact of relay

215 to ground. Relay 216 operates and the

20 following locking circuit is closed for relays

222 and 216: battery through the upper wind-

ing and front contact of relay 222, thence

as traced through the winding of relay 216,

inner right front contact of said relay, and

25 lower contact of relay 222 to ground at the

upper contact of relay 221. Relay 216 opens

the circuit of relay 215 which, after an inter-

val, releases. Relay 222, in operating, op-

erates the relay 217 in a circuit from

30 battery, through the winding of the latter

relay, uppermost contact of relay 222 to

ground.

When relay 215 fully releases, it closes a

circuit for the multi-contact relay 109 which

35 is individual to the marker 103 at the con-

necting device 105. The circuit involved

may be traced from ground, through the

right contact of relay 215, right front con-

tact of relay 216, front contact of relay 217,

40 upper middle contact of relay 222, conduc-

tor 223, winding of relay 109 to battery.

In the manner described above in detail,

relay 115 on releasing causes the operation

of multi-contact relay 106. Thus, with the

45 relays 109 and 106 operated, the sender 100

is connected to the marker 103 instead of

being connected to the marker 102 which

normally is its first choice marker.

It will be noted that the common con-

50 trolling relays associated with the connecting device 205 are taken into operation for

connecting one of the senders in the group

100, 101 to the marker 103. This is due to

the fact that the marker 103 is normally

55 the first choice marker for the group of

senders 200 and 201. During the time that

both groups of senders are having access

to the same marker 103, it is necessary for

both control circuits to cooperate with each

60 other in order to prevent interference.

While the sender 100 is in connection with

the marker 103 through the connecting de-

vice 105, it will be impossible for one of the

senders 200, 201, etc., to obtain connection

65 to the same marker through the connecting

device 205. This is due to the fact that the latter relay, lower front contact of relay 221, common control relay 216 is held energized in series with the relay 222.

When the connection of sender 100 with

the marker 103 is no longer desired, release

70

is effected by opening the circuit of relay

112. Relay 112 causes the release of relays

114 and 116. Relay 116 releases relay 106

and also relay 221. Relay 221 releases re-

lays 222 and 216. In order to place the

75

marker 102 back in service as first choice

for the group of senders 100, 101 it is only

necessary to release the keys 118 and 119.

In a similar manner it will be found from

inspection of the circuits that the operation

of keys 218 and 219 renders the marker

102 accessible to the group of senders 200

and 201.

If it should be desired to place the spare

marker 104 in condition to be selected by

the group of senders 100, 101, keys 118 and

120 are thrown. In this case when relay

115 releases, as above described, it causes

the operation of relay 224 in a circuit trace-

able from ground, through the right con-

tact of relay 115, right front of relay 116,

back contact of relay 117, front off normal

contact of key 118, normal contact of key

119, key 120, conductor 123, and winding

of relay 224 to battery. Relay 224 causes

95 the operation of relay 225 in a circuit simi-

lar to those hereinbefore traced. Relay 225

causes the operation of relay 226 which in

turn causes the operation of relay 227. Relay

227 prepares a locking circuit for itself

100 and relay 225 as follows: battery, through

the upper winding and inner contact of

relay 225, winding and inner right front

contact of relay 227, lower contact of relay

225, and upper contact of relay 224 to

105 ground. Relay 227 releases relay 226. Re-

lay 225 also operates relay 228 in an obvious

circuit. After relay 226 is fully released it

closes a circuit for the multi-contact relay

108, traceable from ground through the

right contact of relay 226, outer right con-

110 tact of relay 227, contact of relay 228, up-

per middle contact of relay 227, conductor

229 and winding of relay 108 to battery.

The spare marker 104 is now rendered ac-

cessible to the group of senders 100 and 101.

In the manner above described, relay 115

releases and causes the operation of relay

106. Both relays 106 and 108 being operat-

115 ed, the sender 100 is connected through

the device 105 to the spare marker 104.

When release is desired, relay 112 is de-

energized, causing the release of relays 114

and 116. Relay 116 releases relay 224 which

in turn releases relays 225 and 227. Relay

225 releases relay 228. Relay 225, in releas-

120 ing, causes the release of relay 108. Thus,

the marker 104 is disconnected from the

125 sender 100.

In a similar manner the spare marker 130

104 may be rendered available to the senders of the second group 200, 201 by throwing the keys 219 and 220.

The invention claimed is:

1. The combination of a plurality of senders, a plurality of switch controlling markers, means for connecting said senders to said markers, each sender normally having access to a different one of the markers, and manual means for rendering a marker which is normally accessible to a particular sender also accessible to another sender.

2. The combination of a plurality of senders, a plurality of switch controlling markers, means for connecting said senders to said markers, each sender normally having access to a different one of the markers, and manual means for rendering any marker inaccessible to the corresponding sender and for rendering one of the remaining markers accessible to said sender.

3. The combination of a plurality of senders, a plurality of switch controlling markers, means for connecting said senders to said markers, each sender normally having access to a different one of the markers, and manual means for disabling one of the markers and means for rendering another marker accessible to a plurality of said senders.

4. In combination, a number of groups of senders, a plurality of switch controlling markers, means for connecting said senders to said markers, each group of senders normally having access to a different one of the markers, and manual means for rendering a marker which is normally accessible to a particular group of senders accessible to another group of senders.

5. In combination, a number of groups of senders, a plurality of switch controlling markers, means for connecting the senders to the markers, each group of senders nor-

mally having access to a different one of the markers, manual means for disabling one of said markers and for rendering the senders of two different groups accessible to one of the remaining markers, and means for preventing more than one sender from making connection with the marker at the same time.

6. In combination, a number of groups of senders, a plurality of switch controlling markers, each group of senders normally having access to a different one of said markers, a multi-contact relay device for connecting each group of senders to the corresponding marker, and manual means for rendering the marker which is normally accessible to a particular group of senders accessible to another group of senders.

7. In combination, a number of groups of senders, a switch controlling marker for each group of senders and normally accessible thereto as first choice, means for connecting the senders to the markers, a spare marker common to all groups of senders, and manual means for rendering said spare marker accessible to any of the groups of senders.

8. In combination, a plurality of senders, a plurality of switch controlling markers, means for connecting said senders to said markers, each sender normally having access to a different one of the markers as first choice, a plurality of keys, and means responsive to the operation of a combination of said keys for rendering the marker which is normally accessible to a particular sender also accessible to another of said senders.

In witness whereof, we hereunto subscribe our names this 27th day of October, A. D. 1923.

SAMUEL B. WILLIAMS.
EARL S. GIBSON.
